UNITED STATES PATENT OFFICE.

ABRAHAM STONE, OF BROOKLYN, NEW YORK, ASSIGNOR TO THE ROSETH CORPORATION, OF BROOKLYN, NEW YORK, A CORPORATION OF NEW YORK.

GARMENT BAG.

Application filed June 12, 1926. Serial No. 115,518.

My invention relates to a new and improved form of garment bag.

One of the objects of my invention is to provide an improved form of side-opening garment bag which shall be dust-proof and moth-proof.

Another object of my invention is to devise a bag of this type which shall be very convenient to manipulate.

10 Another object of my invention is to provide a bag of this type in combination with an improved form of hanger.

Other objects of my invention will be set forth in the following description and drawings which illustrate a preferred embodiment of my device, it being understood that the above general statement of the objects of my invention is intended merely to generally explain the same and not to limit it 20 in any manner.

Fig. 1 is a front elevation.

Fig. 2 is a detail view similar to Fig. 1, the outer part of the bag being omitted to more clearly show the details of construction thereof.

Fig. 3 is a section on the line 3—3 of Fig. 2.

Fig. 4 is a transverse elevation showing how the bag is distended.

25 Figs. 5 and 6 are detail views of the hanger.

The bag 1 is provided with longitudinal edges 2 and 3. The edge 3 is closed and the edge 2 is open, so that this bag is of the side-opening type. The open edge 2 of the bag 35 may be provided with suitable closure members which are not illustrated herein, as they may be of any suitable type.

The hanger for the bag comprises a hook 40 9 which is swiveled to the top 5^a of a bent metal support 5 which is stamped out of any suitable resilient metal. The support 5 is located above the closed top of the bag, which is held between the depending arms 45 of the support 5. One of the arms of support 5 is provided with tongues 8 which can be inserted through slits in the lower support 6 and through an opening 7 in the other arm of the upper support 5. The lower support 6, which is also made of a resilient metal stamping and has two arms, is thus connected to the upper support 5 and the tongues 8 can be bent upwardly as shown

in Fig. 6, so as to permanently connect the two supporting members of the hanger to each other. A spreading member 10 is connected to the lower support 6 by means of a pin extension 11 which projects into the enlarged bottom 6^a of the member 6, so that the member 10 can be freely turned about a vertical axis. The hook 9 can also be freely turned about a vertical axis independently of the member 10.

As shown in Figs. 3 and 4, the bag 1 is provided with a top having a strengthening flap 4 provided with inner extensions and the top of the bag is firmly clamped between the arms of support 5.

When the device is in the position shown in Fig. 3, the bag is in the flat or collapsed position. When, however, the spreading member 10 is turned into the position shown in Fig. 4, this spreads the bag which is suitably supported by the hook 9 from any suitable support, so that the garment which is mounted on a hanger can be readily thrust within the bag, and the hook of the garment hanger can be caused to engage the bottom of the spreading member 10. The member 10 can now be turned into what may 75 be termed the inoperative position shown in Fig. 3 and the open longitudinal edge 2 of the bag can then be suitably closed.

It is obvious that the above construction provides a very simple and efficient means whereby a garment bag can be combined with a supporting hook and with a spreading member.

I have shown a preferred embodiment of my invention, but it is clear that numerous changes and omissions could be made without departing from its spirit.

I claim:

A moth-proof bag open at the side and having a closed top, a lower rigid metal support located in and stiffening said closed top, an upper support having arms external to and embracing the top of the bag, said arms being connected to said inner support, a hook connected to said upper support, and a rigid loop-like spreader made of rigid material and swiveled to the bottom of said lower rigid support.

In testimony whereof I affix my signature.

ABRAHAM STONE.
